(57) **CLAIM**

The ornamental design for an upper platen of a heat press, as shown and described.

DESCRIPTION

FIG. 1 is a perspective view of the top and right sides of an upper platen of a heat press embodying the new design; FIG. 2 is a front view of the upper platen of the heat press thereof;

FIG. 3 is a rear view of the upper platen of the heat press thereof;

FIG. 4 is a right side view of the upper platen of the heat press thereof;

FIG. 5 is a left side view of the upper platen of the heat press thereof;

FIG. 6 is a top plan view of the upper platen of the heat press thereof; and,

FIG. 7 is a bottom plan view of the upper platen of the heat press thereof.

The broken lines showing features of the heat press form no part of the claimed designs of FIGS. 1 through 7.
